UNITED STATES PATENT OFFICE.

JOHN N. NELSON, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND.

OPHTHALMIC MOUNTING.

Application filed November 18, 1927. Serial No. 234,256.

This invention relates to an improved construction of ophthalmic mounting; and has for its object to provide in such a mounting a pair of spaced eyewires connected by a bridge bar, the bar being connected to the eyewires a substantial distance above the medial line thru said eyewires.

A further object of the invention is to groove the ends of the bridge-bar and turn them upwardly to extend along the surface of the eyewires at the point of attachment.

A still further object of the invention is to notch the eyewires to receive the grooved ends of the bridge-bar so that these ends will lie substantially flush with the surface of the eyewires when attached thereto.

With these and other objects in view, the invention consists of certain novel features of construction, as will be more fully described, and particularly pointed out in the appended claims.

In the accompanying drawings:

Fig. 1 is a front view illustrating my improved mounting.

Fig. 2 is an edge view of the mounting.

Fig. 3 is a sectional view of the bridge-bar showing its grooved ends.

Fig. 4 is a section on line 4—4 of Fig. 3 showing the shape of the groove at the end of the bridge-bar.

Fig. 5 is a side elevation of one of the eyewires showing the same notched in its periphery to receive the grooved end of the bridge-bar.

Fig. 6 is an edge view of the eyewires showing the shape of the notch formed therein.

Fig. 7 is a view illustrating the upwardly extending grooved end of the bridge-bar as extending into the notch in the periphery of the eyewires and soldered thereto.

Fig. 8 is a section on line 8—8 of Fig. 7 showing the grooved end of the bridge-bar as engaging the notched portion of the eyewires.

It is found in practice of advantage to connect the thin metal eyewires of an ophthalmic mounting, particularly those made of precious metal, with a bridge-bar which is preferably substantially rigid to support the eyewires firmly in the desired relation and to form the bridge-bar of the same general cross sectional outline as that of the eyewires, the bridge-bar being preferably formed solid with its ends grooved and turned up-

wardly to fit over the periphery of the eyewires and be soldered thereto, the eyewires being preferably notched on its periphery to receive this grooved end of the bridge-bar and permit its surface to lie substantially flush with that of the eyewires so as to preserve the required symmetrical appearance and finish of the mounting, a pair of nose guards being also attached to the inner surfaces of the eyewires to support the mounting on the nose of the wearer; and the following is a detailed description of the present embodiment of the invention and showing one means by which these advantageous results may be accomplished:—

With reference to the drawings, 10 designates the eyewires of my improved mounting which in this case are formed of metal substantially V-shape in cross section on their outer surfaces 11 to present an attractive appearance, and U-shaped on its inner surface 12 to receive the lens 13. These eyewires are preferably notched as at 14 on their peripheries to receive the ends of the bridge-bar. This bridge-bar 15 may be made in any desired shape in cross section but in order to form the same rigid I preferably make it of solid metal and of a shape in cross sectional outline to conform to that of the outline of the eyewires, the ends 16 of this bridge-bar being grooved on their inner surfaces as at 17 in substantially V-shape, as best illustrated in Fig. 4 and these end portions 16 are turned upwardly to extend along the surface of the eyewires and fit into the notches 14 in these eyewires, whereby an extended soldering surface is presented to render the connection to the eyewires strong, substantial and durable, and also by notching the surfaces of the eyewires and grooving the inner surfaces of the bridge-bar ends the surface of the bridge-bar is permitted to lie substantially flush with that of the eyewires forming an invisible joint and yet one which is very strong and durable, also by providing an extended securing surface the thin eyewire is reinforced and strengthened where it is called upon to withstand the greatest strains.

The mounting is provided with a pair of nose guards 18 which support the same on the nose of the wearer and may be provided with temple members 19, if desired.

My improved ophthalmic mounting is very handsome and attractive in appearance and

by my particular means of connecting a bridge member to the eyewires, I have formed a very strong and durable construction.

The foregoing description is directed solely towards the construction illustrated, but I desire it to be understood that I reserve the privilege of resorting to all the mechanical changes to which the device is susceptible, the invention being defined and limited only 10 by the terms of the appended claims.

I claim:

1. An ophthalmic mounting having a pair of spaced eyewires each having a notch therein, a bridge-bar connecting said eyewires at 15 a point adjacent their upper edges, said bar having its ends turned upwardly to conform

to the contour and extend along the eye wires and grooved to fit in said notches, whereby its ends lie substantially flush with the surface of the wires at the point of attachment. 20

2. An ophthalmic mounting having a pair of spaced metal eyewires substantially V-shape in cross sectional outline, a connecting substantially rigid bridge-bar of a similar shape in cross sectional outline with its ends 25 turned upwardly and grooved, the peripheries of the wires being notched to receive the grooved ends of said bar at their point of attachment to lie substantially flush with the surface of the wires.

In testimony whereof I affix my signature. 30
JOHN N. NELSON.
